CODED TRACK CIRCUIT

Arthur L. Jerome, Edgewood, Pa., assignor to The
Union Switch & Signal Company, Swissvale,
Pa., a corporation of Pennsylvania

Application October 29, 1943, Serial No. 508,192

18 Claims. (Cl. 246—38)

My invention relates to railway signaling systems of the coded track circuit type which employ the "coded feed-back" operating principle shown in Letters Patent of the United States No. 2,021,944 to Frank H. Nicholson.

An object of this invention is to provide improved coded track circuits of the type described in which successive impulses of feed-back code are of opposite relative polarity.

A further object of the invention is to provide improved coded feed-back track circuits of the type described in which the feed-back detector relay is of the polarized type and is operated solely by energy supplied from the entrance end of the section to thereby provide a maximum of protection against false operation of the detector relay by foreign current.

Another object of the invention is to provide improved coded track circuits of the type described and incorporating means for discontinuing operation of highway crossing signals when a train vacates the approach section leading to a highway intersection.

A further object of the invention is to provide improved coded track circuits of the type described which are arranged so as to premit impulses of coded alternating current energy of standard pattern to be supplied to the rails of a track section to operate existing cab signal equipment on locomotives operated through the track stretch.

Another object of this invention is to provide improved coded track circuits of the type described in which the impulses of master code are supplied to the track rails in series with the winding of the detector relay to thereby prevent operation of the detector relay by energy stored in the track circuit.

A further object of this invention is to provide improved coded track circuits of the type described in which the impulses of feed-back code are supplied to the track rails in series with the winding of the track relay to thereby prevent operation of the track relay by energy stored in the track circuit.

A further object of the invention is to provide improved coded track circuits of the type described and incorporating means for supplying feed-back energy to the rails of an occupied section to detect when the section is vacated.

Another object of this invention is to provide improved coded track circuits of the type described and incorporating means for selectively controlling the polarity relationship of successive impulses of feed-back and master code sup-

plied to the rails of a track section and for distinguishing between the two types of feed-back energy at the exit end of the section.

A further object of the invention is to provide improved coded track circuits which are arranged so that the master code impulses supplied to the rails of a section are relatively short as long as the section is vacant, and so that when the section is occupied the length of the master code impulses is increased to make these impulses substantially as long as the intervals between impulses.

I shall describe several forms of coded track circuit apparatus embodying my invention and shall then point out the novel features thereof in claims.

In the drawings,

Fig. 1 is a diagram of a section of railroad track equipped with track circuit apparatus embodying my invention, and

Figs. 2 to 11, inclusive, are diagrams showing modifications which I may employ.

Similar reference characters refer to similar parts in each of the several views.

In practicing my invention I employ a track relay and a feed-back detector relay of the stick polar type, while I supply to the section rails impulses of master code which are relatively short and alternate impulses of which are of opposite relative polarity. During the periods between successive impulses of master code I supply to the section rails impulses of feed-back code which are relatively short and alternate impulses of which are of opposite relative polarity. The supply of master code and feed-back energy to the section rails is controlled by impulse relays the contacts of which when released connect the track or feed-back detector relay across the section rails and which when picked up connect the track or feed-back battery across the section rails, while means governed by a contact of a code transmitter or by a contact of the track relay is provided for supplying to the impulse relays, impulses of energy effective to maintain their contacts picked up for a predetermined period only. The polarity of the impulses of master code may be governed by a contact of the feed-back relay or by a contact of the coding device, while the polarity of the impulses of feed-back energy may be controlled by a contact of the track relay or by a contact of a relay controlled by the track relay.

Where cab signals are employed means is provided to operate the impulse relay at the exit end of an occupied section as a repeater of the code transmitter to thereby cause alternating

current impulses of standard code pattern to be supplied to the section rails so that locomotives equipped with existing cab signal apparatus may be operated in track stretches equipped with this track circuit apparatus.

Referring to Fig. 1 of the drawings, there is shown therein a section of railway track having track rails 1 and 2 over which traffic normally moves in the direction indicated by the arrow, that is from left to right. The track rails of the track section are separated from the rails of adjoining sections by insulated joints 3 in the usual manner. A wayside signal S is located at the entrance end of the section and as shown is of the familiar color light type and has a green or clear lamp G, a yellow or caution lamp Y, and a red or stop lamp R.

The track section is equipped with track circuit apparatus embodying this invention. The equipment at the exit end of the section includes a coding relay CTM which is operated at one or another of a plurality of different rates determined by traffic conditions in advance, while the energy for operating relay CTM may be controlled by contacts of continuously operating coding devices 15CT and 180CT. The relay CTM controls the supply of energy to relays MR and MRP, which control the supply of energy from the track battery TB to the section rails and also control connection of the polarized feed-back detector relay K across the section rails, while the relay CTM also controls the polarity of the energy supplied from the track battery to the section rails.

The equipment at the entrance end of the track section includes a polarized track relay TR, a decoding transformer DT, decoding relays H and J, a pole changing relay PC which governs the polarity of the energy supplied from the feed-back battery FB to the section rails, and impulse relays IR and IRP which control connection of the feed-back battery across the section rails and also control connection of the track relay across the section rails.

The equipment at each end of the track section includes a source of direct current, such as a storage battery, not shown, the terminals of which are designated B and C in the drawings.

The equipment is shown in the condition which it assumes when the track stretch is vacant. At this time relay HA, which is governed by traffic in the section in advance of that shown, is picked up and its contact 10 establishes the circuit including a contact of code transmitter 180CT for supplying energy to coding relay CTM so the contacts of relay CTM are picked up and released 180 times a minute.

Each time the contacts of relay CTM pick up or release the contact 11 causes a change in energization of the primary winding of transformer MT, and an impulse of energy is supplied from the transformer secondary winding through a rectifier to relay MR, and also over back contact 12 of relay MR to relay MRP. Accordingly the contacts of relays MR and MRP pick up, and contact 12 of relay MR establishes a stick circuit for relay MRP.

When relays MR and MRP pick up the circuit of relay K is interrupted while the center or neutral terminal of the track battery TB is connected to track rail 2 over front contact 14 of relay MRP and front contact 15 of relay MR. When relay CTM is picked up its contact 16 connects track rail 1 with the upper or positive terminal of the track battery so that energy of normal polarity is supplied to the section rails, while when relay CTM is released contact 16 connects track rail

with the lower or negative terminal of the track battery so that energy of reverse polarity is supplied to the section rails.

The transformer MT and the relay MR are proportioned so that the impulse of energy supplied to relay MR from the transformer on each movement of the contacts of relay CTM will cause the contacts of relay MR to pick up and remain picked up for a predetermined relatively short interval. Relay MRP also picks up when relay MR picks up, while relay MR when picked up establishes a stick circuit for relay MRP so that relay MRP remains picked up as long as relay MR is picked up. On release of relay MR its contact 12 interrupts the stick circuit for relay MRP so relay MRP releases. However, the relay MRP is of a type the contacts of which are slightly slow in releasing so its contacts remain picked up for a short period after release of relay MR.

On release of relay MR its contact 15 interrupts the circuit of the track battery and cuts off the supply of energy to the track rails, but relay K is not connected across the section rails until relay MRP releases. The release period of relay MRP is long enough to permit energy stored in the track circuit to be dissipated so that when relay MRP releases and its contact 13 completes the circuit for connecting relay K across the track rails, there is no danger that the relay K will be operated by energy stored in the track circuit.

It will be seen, therefore, that each time the contacts of relay CTM pick up or release the relays MR and MRP pick up for a short period to cause an impulse of master code to be supplied from the track battery to the section rails, while the relays MR and MRP thereafter release and connect the relay K across the section rails. In addition, it will be seen that the impulses of master code supplied to the section rails are of normal polarity when relay CTM is picked up and are of reverse polarity when relay CTM is released so that successive impulses of master code are of opposite polarity.

The impulses of master code supplied to the track rails feed to the track relay TR over the circuit which is traced from rail 1 through the winding of relay TR, back contact 20 of relay IRP and back contact 21 of relay IR to rail 2. The impulses of master code of normal polarity supplied to relay TR cause the contacts of this relay to move to their left-hand or normal positions, while the impulses of reverse polarity supplied to relay TR move the relay contacts to their right-hand or reverse positions.

On each movement of the contact 22 of relay TR there is a change in energization of the primary winding of transformer DT with the result that an impulse of energy is induced in each of the secondary windings of this transformer. Energy from one of these windings is rectified by contact 24 of relay TR and is supplied to the winding of relay H so that contact 25 of relay H is picked up when and only when relay TR is following code.

Energy from another winding of transformer DT is supplied to relay J through a resonant rectifier unit 180DU, the elements of which are proportioned to supply sufficient energy to relay J to pick up its contacts only when relay TR is responding to energy of 180 code frequency. At this time relay TR is supplied with energy of 180 code frequency so relay J is picked up and energy is supplied to the green lamp G of signal S over the circuit which includes front contact 25 of relay H and front contact 26 of relay J.

Energy from another secondary winding of transformer DT is supplied through an impulse transformer IT to relays IR and IRP which operate in the same manner as relays MR and MRP. When relay IR picks up, its contact 28 establishes a stick circuit for relay IRP, while when relays IR and IRP are picked up, the circuit of relay TR is interrupted and the neutral or center terminal of the feed-back battery FB is connected over front contact 30 of relay IRP and front contact 21 of relay IR to track rail 2. When contact 22 of track relay TR is in its reverse position, energy is supplied through an asymmetric unit 31 to pole changing relay PC and its contact 32 connects track rail 1 to the upper or negative terminal of the feed-back battery FB, while when the contact 22 of relay TR is in its normal position, energy is not supplied to relay PC and its contact 32 is released so that rail 1 is connected to the lower or positive terminal of the battery FB.

On each movement of the contacts of the track relay TR energy is supplied to the relays IR and IRP and their contacts pick up momentarily and connect the battery FB across the section rails. After a brief time interval relay IR releases and interrupts the stick circuit for relay IRP so that it releases and connects the track relay TR across the section rails. On movement of the track relay contacts to their normal positions relay PC is released so the impulse of feed-back energy supplied to the section rails is of normal polarity, while on movement of the track relay contacts to their reverse position relay PC is picked up so the impulse of feed-back energy supplied to the section rails is of reverse polarity.

From the foregoing it will be seen that each time the contacts of relay CTM pick up, the relays MR and MRP pick up momentarily and cause an impulse of master code of normal polarity to be supplied to the track rails. This energy feeds over back contacts 20 and 21 of relays IRP and IR to relay TR and moves its contacts to their normal positions. On this movement of the contacts of relay TR relay PC releases while relays IR and IRP pick up so an impulse of feed-back energy of normal polarity is supplied to the section rails.

When relays IR and IRP pick up the circuit of track relay TR is interrupted, but as picking up of relays IR and IRP is dependent on movement of the contacts of track relay TR, the contacts of relay TR will have completed their movement before relays IR and IRP pick up so interruption of the circuit of relay TR is without consequence. Furthermore, the relay TR is of a type the contacts of which when moved to either position remain in that position until energy of the polarity effective to move the relay contacts to their other position is supplied to the relay. Accordingly, the circuit of the relay TR may be interrupted as soon as its contacts move from one position to the other.

The impulse of feed-back energy of normal polarity supplied to the section rails is supplied over back contacts 15 and 13 of relays MR and MRP to relay K and its contacts move to their normal positions as shown.

The various parts of the apparatus are proportioned so that on picking up of relay CTM the relays MR and MRP will pick up and remain picked up long enough to insure that the impulse of master code supplied to the track rails will operate the track relay TR. The relays MR and MRP release and connect the relay K across the section rails substantially as soon as the relays IR and

IRP pick up to supply an impulse of feed-back energy to the section rails. Furthermore, there is a relatively long period from release of relays MR and MRP until they pick up again so the circuit of relay K is established long enough to insure that the relay will respond to the impulse of feed-back energy supplied over the section rails.

Similarly, when relay CTM releases the relays 10 MR and MRP pick up and cause an impulse of master code of reverse polarity to be supplied to the section rails. When relays MR and MRP pick up the circuit of relay K is interrupted, but before this occurs the relay K will have responded to the impulse of feed-back energy supplied to the track rails. Likewise, at or before the time that the relays MR and MRP pick up, relays IR and IRP will release and establish the circuit of relay TR so that the impulse of master code of reverse polarity feeds to this relay and moves its contacts to their reverse positions so that relays PC, IR and IRP pick up to cause an impulse of feed-back energy of reverse polarity to be supplied to the section rails. This impulse of feed-back energy will move the contacts of relay K to their reverse positions.

The operation of the equipment is such, therefore, that each time the contacts of relay CTM pick up, an impulse of master code of normal polarity is supplied to the section rails, and each time the contacts of relay CTM release, an impulse of master code of reverse polarity is supplied to the section rails. As long as the section is vacant these impulses of master code feed to the track relay and operate it so that relays H and J are picked up, while each time the contacts of the track relay move, the relays IR and IRP pick up and cause an impulse of feed-back energy to be supplied to the section rails. The 30 impulses of feed-back energy occur in the intervals between the impulses of master code, while successive impulses of feed-back energy are of opposite polarity so that the contacts of relay K are operated first to one position and then to the other.

As long as the section is vacant, the contacts of relay K are operated between their two positions and energy is supplied through the transformer KT to the relay KH and the contact 34 of relay KH is picked up. The circuit or circuits governed by contact 34 of relay KH may be employed for any appropriate purpose as, for example, to control lighting of the signal lamps of the signal for the adjacent section in advance or to control locking of a switch, not shown.

When a train enters the track section, the track relay TR is shunted and ceases to follow code, while energy is no longer supplied through the decoding transformer DT to the relays H and J and they release so that the green lamp G is extinguished and energy is supplied to the red lamp R of signal S over back contact 25 of relay H. In addition, energy is no longer supplied to relays IR and IRP and they remain released and do not supply energy from the feed-back battery to the section rails. As the supply of feed-back energy to the section rails is cut off, relay K ceases to operate and relay KH releases.

At this time relay CTM continues to operate so impulses of master code are supplied to the track rails, and when the section is vacated, these feed to the track relay and operate it so that relays IR and IRP again cause feed-back energy to be supplied to the section rails, while relay H is picked up and relay J may also be picked up.

The feed-back energy supplied to the section rails feeds to the relay K and operates it so that energy is supplied through transformer KT to relay KH.

In this system the feed-back detector relay K is operated solely by energy supplied from the entrance end of the track section, while in order to operate the relay K, successive impulses of feed-back energy must be of opposite polarity. This substantially eliminates the possibility of operation of relay K by foreign current when the track section is occupied.

When the section is occupied, the track relay is shunted and does not cause relays IR and IRP to supply impulses of feed-back energy to the track rails. At this time relay CTM continues to operate so relays MR and MRP pick up to cause impulses of master code to be supplied to the section rails and at the same time to interrupt the circuit of relay K, while the relays MR and MRP subsequently release and connect the relay K across the section rails. The relay K is of the stick polar type and when the circuit of the relay winding is interrupted, the relay contacts remain in the position which they then occupy.

Foreign current when present is of one relative polarity. Accordingly, when relays MR and MRP release at a time when the section is occupied and foreign current of a value high enough to operate relay K is present, the foreign current will hold the contacts of relay K in the position which they then occupy if the position of the contacts of relay K and the polarity of the foreign current are in correspondence. If the position of the contacts of relay K and the polarity of the foreign current are out of correspondence, the energy supplied to relay K the first time the winding of relay K is connected across the section rails will move the contacts of relay K into correspondence with the polarity of the foreign current, while the relay contacts are held in this position by the energy supplied to relay K during subsequent periods in which the relay winding is connected across the section rails.

Energy is supplied through the transformer KT to the relay KH only when the contacts of relay K are continuously moved between their two positions, and as foreign current supplied to relay K serves to hold the relay contacts in one position there is no possibility that the supply of foreign current to the relay K will result in energization of relay KH.

The track circuit provided by this invention may be modified to provide for the supply of coded alternating current cab signal control energy to the rails of an occupied section and Fig. 2 shows such a modification.

Construction and operation of modification shown in Fig. 2

The modification shown in Fig. 2 is similar to that shown in Fig. 1, but differs therefrom in that a track transformer TT has its secondary winding connected in series with the track battery TB, while the equipment at the exit end of the section is arranged so that when the section is occupied the relays MR and MRP operate as repeaters of the coding relay CTM instead of as impulse relays.

The equipment at the entrance end of the section shown in Fig. 2 differs from that shown in Fig. 1 in that means is provided for supplying feed-back energy to an occupied section to reset the track circuit when the section is vacated.

A wayside signal is not shown in Fig. 2 but such a signal may be provided if it is desired.

The modification shown in Fig. 2 is intended for use in track stretches through which are operated locomotives equipped with cab signal apparatus responsive to flow of coded alternating current in the track rails. The locomotive cab signal equipment may be constructed as shown in Letters Patent of the United States No. 1,986,679 to Lloyd V. Lewis.

The apparatus of Fig. 2 is shown in the condition which it assumes when the track stretch is vacant. At this time relay KH is picked up and its contact 34 establishes the circuit of contact 11 of coding relay CTM so that energy is supplied through the transformer MT to relays MR and MRP and they operate as explained in connection with Fig. 1 to supply impulses of master code of alternate polarity to the section rails, and to connect the relay K across the section rails in the periods between the impulses of master code to the track rails.

In addition, as relay KH is picked up, its contact 35 short-circuits the primary winding of the track transformer TT.

The master code supplied to the section rails operates the track relay TR so that energy is supplied through the decoding transformer DT to the relay H, and it is picked up so that its contacts 36 and 37 connect the primary winding of impulse transformer IT to a secondary winding of transformer DT so that, on each movement of the contacts of the track relay, an impulse of energy is supplied through the impulse transformer to the relays IR and IRP and they operate in the manner explained in connection with Fig. 1 to supply impulses of feed-back energy to the section rails. In addition, contact 38 of relay H connects relay PC to a stationary contact associated with track relay contact 22 so that relay PC causes successive impulses of feed-back energy to be of opposite polarity.

When a train moving in the normal direction of traffic enters the track section, the relay K is shunted and ceases to follow code so energy is no longer supplied through the transformer KT to relay KH and the contacts of relay KH release so that contact 34 interrupts the circuit of contact 11 of coding relay CTM and establishes the circuit of coding relay contact 40. Accordingly, energy is no longer supplied through the transformer MT to the relays MR and MRP, but each time the contacts of relay CTM pick up, energy is supplied over its front contact 40 to the relays MR and MRP so that they pick up and remain picked up throughout the entire picked-up period of the contacts of relay CTM. In addition, when relay KH releases, its contact 35 establishes the circuit to supply energy to the primary winding of track transformer TT from a source of alternating current energy, the terminals of which are designated BX and CX.

Accordingly, each time the contacts of relay CTM pick up, the contacts of relays MR and MRP pick up so that the track transformer TT is connected across the section rails and alternating current is supplied to the section rails. At this time the relays MR and MRP are direct repeaters of the relay CTM so the alternating current supplied to the track rails is coded in the normal manner and will operate cab signal equipment of standard construction.

When the section is occupied, the track relay is shunted and energy is no longer supplied through the transformer DT to relay H so relay

H releases and its contacts 36 and 37 transfer connection of the primary winding of transformer IT from a secondary winding of decoding transformer DT to contacts of a coding device 20CT, while contact 38 of relay H transfers control of relay PC from track relay contact 22 to a contact of coding device 20CT. The contact of the coding device 20CT is continuously operated between its two positions so that when relay H is released, the two portions of the primary winding of transformer IT are alternately energized, while each time the contact of the device 20CT moves to its lower position, energy is supplied to the relay PC. Accordingly, on movement of the contact of the device 20CT to either of its two positions, an impulse of energy is supplied through the transformer IT to the relays IR and IRP so that they pick up momentarily and establish the circuit of the battery FB and thus cause impulses of feed-back energy to be supplied to the section rails, while relay PC causes alternate impulses of feed-back energy to be of opposite relative polarity. As long as the section is occupied, the relay K is shunted and the impulses of feed-back energy supplied do not operate the relay K.

When the train vacates the section, the impulses of feed-back energy feed to the relay K and operate it to cause energy to be supplied through the transformer KT to the relay KH.

At the time the section is vacated, the relays MR and MRP are being picked up and released at the rate determined by the rate of operation of relay CTM. The rate of operation of the coding device 20CT is substantially different from that of the coding devices 75CT and 180CT with the result that there are frequently recurring periods in which the relays IR and IRP are picked up to cause impulses of feed-back energy to be supplied to the track rails, and the relays MR and MRP are released to permit energy from the track rails to feed to the relay K. Accordingly, the feed-back energy will operate the relay K so that relay KH is picked up.

When the contacts of relay KH pick up, contact 35 cuts off the supply of energy to the track transformer TT and short-circuits the track transformer primary winding, while contact 34 interrupts the circuit of contact 49 of coding relay CTM and establishes the circuit of contact 41 of relay CTM. Accordingly, relays MR and MRP cease to operate as repeaters of relay CTM, while impulses of energy are supplied through transformer MT to relays MR and MRP so that they operate in the usual manner to supply impulses of master code of alternate relative polarity to the section rails.

Because of the difference in the rate of operation of the relays MR and MRP and of the relays IR and IRP, there are frequently recurring periods during which the track relay TR is connected across the section rails at a time when impulses of master code are supplied to the section rails. The impulses of master code, therefore, will feed to the track relay and operate it so that energy is supplied through the decoding transformer DT to relay H, and its contacts pick up so that the primary winding of transformer IT is transferred from coding device 20CT to a secondary winding of transformer DT, while control of relay PC is transferred from coding device 20CT to contact 22 of the track relay TR. The equipment at the entrance end of the section now operates in the normal manner to supply an impulse of feed-back energy to the section rails following each movement of the track relay con-

75 tact, while the relay PC causes alternate impulses of feed-back energy to be of opposite polarity.

From the foregoing it will be seen that, when the section is vacant, an impulse of master code is supplied to the section rails each time the contacts of relay CTM pick up or release, while the impulses of master code are much shorter than the picked-up and released periods of the contacts of relay CTM. In addition, when the section is vacant, the supply of feed-back energy is governed by response of the track relay to impulses of master code. When the section is occupied, control of relays MR and MRP is transferred to a contact of relay CTM so that these relays operate as repeaters of the relay CTM and supply to the track rails coded energy in which the energy impulses are substantially as long as the intervals between energy impulses so that the cab signal control energy supplied to the section rails is of standard pattern and will operate existing cab signal apparatus. In addition, it will be seen that, when the section is occupied, the equipment at the entrance end of the section operates to supply impulses of feed-back energy to the section rails to reset the track circuit when the section is vacated.

In the modification shown in Fig. 2, a code transmitter 20CT is provided to cause feed-back energy to be supplied to the rails of an occupied section. This supply of feed-back energy to the rails of an occupied section can be effected by interaction of the relays at the entrance end of the section, thereby eliminating the need for the coding device 20CT, and Fig. 3 is a diagram illustrating such a modification.

Construction and operation of modification shown in Fig. 3

40 In the modification shown in Fig. 3, the wire leading to relays IR and IRP is connected over front contact 42 of relay H to an output terminal of the rectifier associated with transformer IT, and is connected over back contact 42 of relay H to contact 43 of relay PC, while contact 38 of relay H when picked up connects the winding of relay PC to track relay contact 22 and, when released, to back contact 45 of relay IRP. Contact 46 of relay H controls the circuit of a winding of relay PC to render the relay slow acting when relay H is released.

45 The equipment is shown in the condition which it assumes when the track section is vacant. At this time, energy is supplied through the decoding transformer DT to relay H so its contacts are picked up with the result that energy is supplied from the impulse transformer IT to relays IR and IRP and relay PC is controlled by track relay contact 22 so that impulses of feed-back energy of alternately opposite polarity are supplied to the track rails in the same manner as explained in connection with Fig. 1.

50 When the section is occupied, the track relay is shunted and energy is no longer supplied through the transformer DT to relay H so relay H releases and transfers control of relay PC to a back contact of relay IRP and transfers control of relays IR and IRP to a front contact of relay PC. On release of relays IR and IRP, energy is supplied over back contact 45 of relay IRP and back contact 38 of relay H to relay PC and its contacts pick up so that contact 43 establishes the circuit of relays IR and IRP. Accordingly, relays IR and IRP pick up and establish the circuit for supplying energy from the battery FB

to the section rails, while contact 45 of relay IRP interrupts the circuit of relay PC. At this time, however, the lower winding of relay PC is short-circuited over back contact 46 of relay H so the relay is rendered slow to release and to pick up, and on picking up of relay IRP and resultant interruption of the circuit of relay PC, its contacts remain picked up for a short period and its contact 43 maintains the circuit of relay IR, while its contact 32 maintains the circuit of the upper portion of the battery FB so that an impulse of feed-back energy of reverse polarity is supplied to the section rails.

After expiration of the release time of relay PC, its contacts release so contact 32 interrupts the supply of energy from the upper portion of battery FB and establishes the circuit to supply energy from the lower portion of battery FB so feed-back energy of normal polarity is supplied to the section rails. When relay PC releases, its contact 43 interrupts the circuit of relay IR and, after a short time interval, relay IR releases to interrupt the supply of energy from the battery FB to the section rails and to also interrupt the circuit of relay IRP. Accordingly, relay IRP releases and completes connection of the track relay TR across the section rails while contact 45 of relay IRP establishes the circuit to supply energy to relay PC. Because of the slow acting characteristic of relay PC at this time, its contacts do not pick up for a short period. This insures that relays IR and IRP will remain released and maintain the circuit of the track relay for a substantial period so that, when the section is vacated, impulses of master code can feed to the track relay and operate it to pick up relay H and reset the track circuit apparatus.

When relay PC picks up, its contact 43 establishes the circuit to supply energy to relays IR and IRP so that they pick up and the cycle just described is repeated.

When the section is vacated, the feed-back energy supplied to the section rails feeds to the feed-back detector relay at the exit end of the section and operates it as explained in connection with Fig. 2 to reset the equipment at the exit end of the section and thus cut off the supply of alternating current cab signal control energy to the section rails and reestablish the supply of impulses of master code of alternate relative polarity to the section rails. These impulses of energy feed to the track relay TR during the released periods of the relays IR and IRP and operate the track relay so that energy is supplied to relay H. When relay H picks up, its contact 42 transfers control of relays IR and IRP to the impulse transformer IT, while contact 38 of relay H transfers control of relay PC to track relay contact 22, and contact 46 of relay H interrupts the circuit of the lower winding of relay PC. The equipment now operates in the normal manner as explained in detail above.

The various parts of the system shown in Fig. 3 are selected and proportioned so that the rate of operation of the relays IR, IRP and PC, when the section is occupied, is substantially different from that of the code transmitters which govern the supply of master code to the section rails. This insures that there will be frequently recurring periods during which impulses of feed-back energy can feed to the feed-back detector relay and during which impulses of master code can feed to the track relay so that resetting of the track circuit when the section is vacated will be prompt and positive.

In the modifications previously described, a repeater relay IRP for relay IR is provided to delay connection of the track relay TR across the section rails until energy stored in the track circuit has been dissipated to thereby prevent operation of the track relay by this energy. The track relay may also be protected from operation by stored energy and against overlapping contacts on the relay IR by supplying energy from the battery FB to the section rails in series with the track relay winding, and Fig. 4 is a diagram showing such a modification.

Construction and operation of modification shown in Fig. 4

Referring to Fig. 4, the equipment shown therein is similar to that employed at the entrance end of the section shown in Fig. 1, but differs therefrom in that a contact 48 of the track relay TR controls the polarity of the energy supplied from the feed-back battery FB, thereby eliminating the need for the relay PC, while a contact of relay IR controls the circuits of the battery FB and of the track relay TR.

When the relay IR is released, its contact 47 interrupts the circuit of the battery FB and establishes the circuit to connect the winding of the track relay TR across the section rails so that master code may feed to the track relay. On the supply of an impulse of master code of reverse polarity to the track relay, its contacts move from their normal to their reverse positions, while an impulse of energy is supplied through transformer IT to relay IR and its contact 47 picks up to interrupt the circuit connecting track relay TR directly across the section rails and to connect the winding of the track relay across the section rails in series with the right-hand portion of the battery FB so that energy is supplied from the battery to the section rails through the track relay winding.

At this time the positive terminal of the right-hand half of the battery FB is connected over front contact 47 of relay IR to the right-hand terminal of the winding of the track relay and through this winding to the track rail 1, while the negative terminal of this portion of the battery is connected over reverse polar contact 48 of relay TR to rail 2. Accordingly, at this time an impulse of feed-back energy of normal polarity is supplied to the section rails, while the direction of flow of energy through the winding of relay TR is such that the contacts of relay TR are held in their reverse positions.

On release of the contact 47 of relay IR, the circuit of the battery FB is interrupted and the winding of relay TR is connected directly across the section rails. On interruption of the supply of energy from the battery FB to the section rails, energy stored in the track circuit continues to flow in the same direction that it has been flowing, and energy supplied from the track circuit to the winding of the track relay TR operates to hold the relay contacts in the position which they then occupy, that is, their reverse positions.

The next impulse of master code supplied to the section rails will be of normal polarity, and this energy will feed over back contact 47 of relay IR to the winding of relay TR and will move the contacts of relay TR to their left-hand or normal positions. On this movement of the track relay contacts, an impulse of energy is supplied through the transformers DT and IT to the relay IR and its contact 47 picks up to connect the left-hand portion of battery FB across the section rails in

series with the winding of the track relay TR. The positive terminal of this portion of the battery FB is connected over normal polar contact 48 of relay TR to track rail 2, while the negative terminal of this portion of the battery is connected over front contact 47 of relay IR to the left-hand terminal of the winding of relay TR, and through this winding to track rail 1. Accordingly, an impulse of feed-back code of reverse polarity is supplied to the section rails, while energy flows through the winding of relay TR from its left-hand to its right-hand terminal so the energy flowing through the relay winding holds the relay contacts in the positions which they then occupy, that is, their normal positions.

On release of the relay IR, the circuit of the battery FB is interrupted and relay TR is connected directly across the section rails. When the circuit of the battery FB is interrupted, energy stored in the track circuit continues to flow in the direction in which it has been flowing so this energy operates to hold the contacts of relay TR in the position which they then occupy, that is, their normal positions.

On continued supply of master code to the track relay, the contacts of this relay move from one position to the other, while after each movement of the track relay contacts, the impulse relay IR picks up to cause an impulse of feed-back energy to be supplied to the track rails over a circuit which includes the winding of the track relay in series therewith, and the direction of flow of feed-back energy through the track relay winding is such as to hold the track relay contacts in the position which they then occupy. In addition, the direction of flow of energy through the track relay winding is such that when relay IR releases and interrupts the circuit of the battery FB, energy stored in the track circuit will flow through the track relay winding in the direction to maintain the relay contacts in the position which they already occupy so that there is no possibility that the track relay will be operated by energy stored in the track circuit.

The principle shown in Fig. 4 for preventing operation of the track relay by energy stored in the track circuit may also be employed to protect the feed-back detector relay, and Fig. 5 is a diagram illustrating such a modification.

Construction and operation of modification shown in Fig. 5

In the modification shown in Fig. 5, the polarity of the energy supplied from the track battery TB to the section rails is controlled by contact 50 of the feed-back detector relay K, while the supply of energy to the transformer MT is controlled by contacts of the coding devices instead of by a relay which repeats these devices.

When relay HA is picked up, its contact 10 establishes the circuit controlled by the contact of coding device 180CT for supplying energy to the primary winding of transformer MT, so that each time the contact of coding device 180CT picks up or releases, an impulse of energy is supplied through the transformer MT to relay MR.

When contact 15 of relay MR picks up at a time when the contact 50 of relay K is in its normal position, as shown, energy is supplied from the left-hand portion of the track battery to the section rails over the circuit which is traced from the positive terminal of this portion of the battery over front contact 15 of relay MR to rail 2, thence through the track relay, not shown, to rail 1, through winding of relay K from left to right, 75

and over normal polar contact 50 of relay K to the negative terminal of the battery. The energy flowing through the winding of relay K holds the relay contacts in their normal positions. When 5 relay MR releases, its contact 15 interrupts the circuit of the battery TB and connects relay K across the section rails, while energy stored in the track circuit will flow through the winding of relay K in the direction to maintain its contacts in their normal positions.

When relay MR picks up at a time when the contacts of relay K are in their reverse positions, energy is supplied from the right-hand portion of battery TB to the section rails over the circuit 15 which is traced from the positive terminal of this portion of the battery over reverse polar contact 50, through the winding of relay K from right to left to rail 1, thence through the track relay winding, not shown, to rail 2, and over front contact 15 of relay MR to the negative terminal of this portion of the track battery. The energy supplied through the winding of relay K holds the relay contacts in their reverse positions, while on release of relay MR the supply of energy from the track battery to the section rails is cut off and the relay K is connected across the track rails, and energy stored in the track circuit will flow through the winding of relay K in the direction to hold the relay contacts in their reverse positions.

If, for any reason, the movable contact 15 of relay MR should engage its front and back contacts at the same time, the track battery will be short-circuited and energy will not be supplied 35 from the track battery to relay K which might cause operation of relay K.

In some situations it is necessary to divide a track section into two subsections, and to provide means for repeating into the rearward one 40 of the sections the master code supplied to the forward one of these sections and to also provide means governed by occupancy of the rearward one of these sections for controlling the supply of feed-back energy to the forward one 45 of these sections, and Fig. 6 is a diagram illustrating code repeating equipment which may be employed at a cut-section installed for the control of a highway crossing signal.

Cut-section facilities of Fig. 6

The equipment of Fig. 6 is similar to that shown in Figs. 4 and 5 and employs the series supply of energy from the feed-back and track batteries shown in Figs. 4 and 5. It is contemplated that the equipment at the entrance 55 end of the track section will be arranged as shown in either Fig. 2 or Fig. 3 so that feed-back energy is supplied to the section rails when the section is occupied. The equipment at the exit end of the track section is arranged as shown in Fig. 1.

When the track section is vacant, master code supplied at the exit end of the section feeds to the track relay TR of the forward subsection and operates it so that energy is supplied through the decoding transformer DT and transformer MT to relay MR so that relay MR picks up to supply energy from battery TB to the section rails, while at this time relay K is operated by feed-back energy so that its contact 50 causes alternate impulses of master code to be of opposite relative polarity. At this time, relay KH is picked up and its contact 52 establishes the circuit for supplying energy from the transformer IT to relay IR so that it picks up to supply energy

from battery FB to the section rails. Accordingly, each time the contacts of relay TR move from one position to the other, relay IR picks up to supply an impulse of feed-back energy to the forward subsection, and relay MR picks up to supply an impulse of master code to the rearward subsection. The relay MR, therefore, repeats the relay TR so energy of the same code frequency is supplied to the rearward subsection and is supplied to the forward subsection.

As the relay KH is picked up, its contact 54 interrupts the circuit of the crossing signals XS to prevent operation of these signals at this time.

When a train travelling in the normal direction of traffic enters the rearward subsection, it cuts off the supply of feed-back energy over the section rails so that relay K ceases to operate. This causes relay KH to release so that contact 54 establishes the circuit of the crossing signals XS and they operate to warn users of the highway of the approach of the train.

In addition, on release of relay KH, contact 52 interrupts the circuit of relay IR so that it remains released and does not supply feed-back energy to the forward subsection. Accordingly, the equipment at the exit end of the section operates to provide an indication at that point that the section is occupied.

At this time, the equipment at the entrance end of the rearward subsection operates as explained in connection with Fig. 2 or 3 to cause impulses of feed-back energy to be supplied to the section rails.

When the train advances into the forward subsection, the track relay TR is shunted and ceases to follow code so energy is no longer supplied through transformers DT and MT to relay MR and its contact remains released so that energy is no longer supplied from battery TB to the rails of the rearward subsection, while relay K is connected across the section rails.

When the train vacates the rearward subsection, impulses of feed-back energy supplied at the entrance end of this subsection feed to relay K and operate it so that energy is supplied through the decoding transformer KT to relay KH. Accordingly, relay KH picks up and its contact 54 interrupts the circuit of the crossing signals XS and they cease operating, while contact 52 of relay KH establishes the circuit of relay IR. However, at this time, relay TR is shunted so energy is not supplied to relay IR and its contact remains released.

When the train vacates the forward subsection, impulses of master code supplied at the exit end of this subsection feed to the track relay TR and operate it so that energy is supplied through the transformer DT to the relays IR and MR and the relay IR operates to supply feed-back energy to the forward subsection, while the relay MR operates to supply impulses of master code to the rearward subsection. At this time, relay K is being operated by feed-back energy supplied at the entrance end of the rearward subsection so the contacts of relay K are constantly being moved between their two positions. Accordingly, on repeated picking up of the contact 15 of relay MR to establish the circuit of the track battery TB, there are frequent reversals in the polarity of the energy supplied to the section rails. As explained above in connection with Figs. 2 and 3, the frequency of the feed-back energy is substantially different from that of the master code supplied to the section rails so

there are frequently recurring periods in which master code supplied to the track rails may feed to the track relay and operate it to reset the apparatus at the entrance end of the section so that thereafter the supply of feed-back energy to the section rails is governed by operation of the track relay.

From the foregoing, it will be seen that the equipment shown in this modification operates to initiate operation of the highway crossing signals when a train enters the track section and to discontinue operation of the crossing signals when the train vacates the rearward subsection, while the equipment also operates to provide an indication of occupancy of the track section at the exit end of the section as long as either subsection is occupied.

In the modification described above, the relays IR and IRP which control the supply of feed-back energy to the section rails have been energized through an impulse transformer which is proportioned to limit the value of the energy impulse supplied to the relay IR so that the contacts of relay IR will remain picked up for a predetermined period. It is possible to control the supply of energy to relays IR and IRP by contacts of the relays TR and PC and thus eliminate the transformer IT, and Fig. 7 is a diagram showing such a modification.

30 Construction and operation of modification shown in Fig. 7

The apparatus shown in Fig. 7 is similar to that employed at the entrance end of the section shown in Fig. 1, but differs therefrom in that the supply of energy to relays IR and IRP is controlled by contact 55 of relay TR and by contact 56 of relay PC.

When the contacts of relay TR are in their normal positions, as shown, contact 22 of relay TR interrupts the circuit of relay PC so the contacts of relay PC are released and contact 56 interrupts the circuit of relays IR and IRP.

On movement of the track relay contacts to their reverse positions, contact 22 establishes the circuit for supplying energy to relay PC, while contact 55 of relay TR establishes the circuit including back contact 56 of relay PC for supplying energy to relays IR and IRP. The supply of energy to relays IR and IRP is cut off as soon as relay PC picks up, but relay PC remains released long enough subsequent to movement of the track relay contacts to their reverse positions to permit sufficient energy to be supplied to relays IR and IRP to cause their contacts to pick up and to cause the contacts of relay IR to remain picked up for a predetermined period.

Similarly, on movement of the track relay contacts from their reverse to their normal positions, energy is supplied to relays IR and IRP over the circuit which includes front contact 56 of relay PC and normal polar contact 55 of relay TR. At this time, track relay contact 22 interrupts the circuit of relay PC so its contacts release and contact 56 cuts off the supply of energy to relay IR. However, the contacts of relay PC remain picked up long enough subsequent to movement of the contacts of relay TR to their normal positions to permit sufficient energy to be supplied to relays IR and IRP to cause their contacts to pick up and to cause the contacts of relay IR to remain picked up for a predetermined period.

When the section is occupied, the contacts of the track relay remain in one position or the

other, while the contacts of relay PC remain picked up or released, depending on the position of the track relay contacts, and the circuit of relays IR and IRP will be interrupted so that these relays are released and establish the circuit of the track relay. Accordingly, master code will be supplied to the track relay as soon as the section is vacated.

The principle employed in Fig. 7 for the control of the relays IR and IRP may also be employed to control the relays MR and MRP and Fig. 8 is a diagram illustrating such a modification.

Modification shown in Fig. 8

The equipment shown in Fig. 8 is similar to that employed at the exit end of the track section shown in Fig. 1 except that the supply of energy to the relays MR and MRP is controlled by a contact of the relay CTM and by contacts of the coding devices 180CT and 75CT instead of being supplied through a transformer MT.

When relay HA is picked up, its contact 10 establishes the circuit controlled by coding device 180CT for supplying energy to coding relay CTM and to relays MR and MRP over back contact 11 of relay CTM. In addition, contact 10 of relay HA establishes a circuit controlled by a contact of coding device 180CT for supplying energy to relays MR and MRP over front contact 11 of relay CTM.

When the contact of coding device 180CT is picked up, as shown, energy is supplied over front contact 10 of relay HA to relay CTM so that the contacts of relay CTM are picked up and contact 11 interrupts the circuit of relays MR and MRP. On release of the contact of coding device 180CT, the supply of energy to relay CTM is cut off, while energy is supplied over front contact 10 of relay HA and front contact 11 of relay CTM to relays MR and MRP. The supply of energy to relays MR and MRP is cut off as soon as contact 11 of relay CTM releases, but the contacts of relay CTM remain picked up long enough subsequent to release of the coding device contact to permit sufficient energy to be supplied to relays MR and MRP to pick up their contacts and to maintain the contacts of relay MR picked up for a predetermined period, after which the relays MR and MRP release and connect relay K across the section rails.

Similarly, when the contacts of coding device 180CT pick up, energy is supplied to relay CTM, and is also supplied over back contact 11 of relay CTM to relays MR and MRP. The supply of energy to relays MR and MRP is cut off as soon as contact 11 of relay CTM picks up, but sufficient energy is supplied to relays MR and MRP prior to picking up of the contacts of relay CTM to pick up the contacts of relays MR and MRP and to keep the contacts of relay MR picked up for a predetermined period.

An asymmetric unit 62 is included in series with the circuit for supplying energy to relays MR and MRP to prevent interference with the release time of these relays by the relay CTM.

It will be seen that the apparatus of Fig. 8 operates to supply energy to relays MR and MRP when the contacts of relay CTM and of coding device 180CT are out of correspondence. The relays MR and MRP, therefore, pick up each time the coding device contacts pick up or release.

When relay HA is released, the supply of energy to relay CTM and to relays MR and MRP is controlled by a contact of coding device 75CT,

while the equipment operates in the manner explained in detail above.

The principle employed in the modification shown in Figs. 7 and 8 is also applicable to track sections in which cab signal energy is supplied to the rails of the section when the section is occupied, and Fig. 9 is a diagram showing this application of the invention.

Modification shown in Fig. 9

In Fig. 9 only the equipment at the exit end of the section is shown, and the equipment at the entrance end of the section may be arranged as shown in Fig. 2 or 3. The equipment of Fig. 9 is shown in the condition which it assumes when the track section is vacant. At this time, relay K is operated by feed-back energy and relay KH is picked up so that its contact 35 short-circuits the primary winding of track transformer TT, while contact 64 of relay KH establishes the circuit controlled by code transmitters 180CT and 75CT for supplying energy to coding relay CTM, and the equipment operates in the same manner as that shown in Fig. 8.

When a train enters the track section and cuts off the supply of feed-back energy to relay K, the relay KH releases and its contact 35 establishes the circuit for supplying energy to track transformer TT, while contact 64 of relay KH interrupts the circuit of relay CTM so that the contacts of relay CTM remain released. On continued operation of the code transmitter 180CT, energy is supplied over back contact 11 of coding relay CTM to relays MR and MRP during the picked-up periods of the contact of code transmitter 180CT so the relays MR and MRP operate as repeaters of the code transmitter. During the picked-up periods of the relays MR and MRP, energy is supplied from the track transformer TT to the section rails, and as the relays MR and MRP operate as repeaters of the code transmitter at this time, the impulses of alternating current supplied to the section rails are of standard pattern and will operate cab signal equipment of standard construction.

When the section is vacated, feed-back energy supplied at the entrance end of the section feeds to relay K during the released periods of the relays MR and MRP and operates relay K to pick up relay KH and cut off the supply of energy to track transformer TT and establish the circuit of coding relay CTM so that the equipment operates to supply impulses of master code of alternately opposite polarity to the section rails.

The principle employed in the modifications shown in Figs. 7, 8 and 9 is also applicable to the track relay end of a track section in which feed-back energy is supplied to the section rails when the section is occupied, and Fig. 10 is a diagram showing this application of the invention.

Modification shown in Fig. 10

The apparatus of Fig. 10 is similar to that of Figs. 3 and 7 and is shown in the condition which it assumes when the track section is vacant. At this time, the track relay TR is operated by master code energy supplied over the section rails and relay H is picked up so its contact 38 connects relay PC to a contact of the track relay and its contact 42 connects relays IR and IRP to the circuit governed by contact 55 of relay TR and contact 56 of relay PC. Accordingly, the equipment operates in the same manner as that shown in Fig. 7 to supply impulses of feed-back energy of alternate polarity to the section rails.

When a train enters the section, the track relay ceases to operate and relay H releases so that contact 38 transfers control of relay PC to back contact 45 of relay IRP and contact 42 transfers control of relays IR and IRP to front contact 43 of relay PC. The equipment now operates in substantially the same manner as that shown in Fig. 3. On release of relay IRP, energy is supplied to relay PC and its contacts pick up to cause energy to be supplied to relays IR and IRP so that they establish the circuit including front contact 32 of relay PC for supplying energy from battery FB to the section rails, while contact 45 of relay IRP interrupts the circuit of relay PC. Accordingly, relay PC releases so that energy is supplied from battery FB to the section rails over back contact 32, while contact 43 interrupts the circuit of relays IR and IRP and they release so the cycle is repeated. At this time, the lower winding of relay PC is short-circuited over contact 46 of relay H so relay PC is slow to pick up and release and its contacts remain released long enough during each cycle to permit master code supplied to the section rails to operate the track relay and reset the apparatus when the section is vacated.

In some situations, it is desirable to employ the feed-back energy for a track section to indicate occupancy of the section in the rear of that section as well as of the section over which the feed-back energy is supplied. This result may be accomplished by controlling the polarity relationship of the feed-back impulses with respect to the master code impulses, and Fig. 11 is a diagram illustrating such a modification.

Modification shown in Fig. 11

The apparatus shown in Fig. 11 is similar to that shown in Fig. 1 but differs therefrom in that the equipment at the entrance end of the track section includes a relay KHB which is governed by traffic conditions in the adjacent section in the rear and controls connection of relay PC to a normal or a reverse polar contact of the track relay. The equipment at the exit end of the section includes a polar relay KP and a biased polar relay KN, which are energized in series from the secondary winding of the decoding transformer KT, while the polarity of the energy supplied to these relays is determined by contact 65 of relay CTM. The relays KP and KN are energized through asymmetric units in the manner shown in Letters Patent of the United States No. 2,324,200, granted July 13, 1943 to Arthur E. Dodd.

The equipment is shown in the condition which it assumes when the track stretch is vacant. At this time, relay HA is picked up so relay CTM is operated by energy of 180 code frequency, while contact 66 of relay KHB is picked up and connects relay PC to reverse polar contact 22 of relay TR.

Each time the contacts of relay CTM pick up, an impulse of energy is supplied through transformer MT to relays MR and MRP and they pick up so that energy is supplied from the upper portion of track battery TB to the section rails. The positive terminal of this battery is connected to track rail 1 so the master code supplied to the section rails may be considered to be of "normal" polarity.

Each time the contacts of relay CTM release, an impulse of energy is supplied to the section rails from the lower portion of the track battery. At these times, the positive terminal of the track

battery is connected to rail 2 so the master code may be considered to be of "reverse" polarity.

The impulses of master code of normal polarity feed to the track relay TR and move its contacts to their left-hand or normal positions, with the result that an impulse of energy is supplied to relays IR and IRP so that they pick up to supply an impulse of feed-back energy to the section rails, while relay PC releases so that the impulse of feed-back energy is supplied from the lower portion of the battery FB. The positive terminal of this portion of the battery is connected to track rail 1 so the impulse of feed-back energy supplied to the section rails may be considered to be of "normal" polarity.

Similarly, when an impulse of master code of reverse polarity feeds to the track relay, an impulse of feed-back energy is supplied to the section rails from the upper portion of battery FB. The positive terminal of this portion of the battery is connected to track rail 2 so that the impulse of feed-back energy supplied at this time is of "reverse" polarity.

Accordingly, when relay KHB is picked up, each impulse of master code of "normal" polarity is followed by an impulse of feed-back code of "normal" polarity, and each impulse of master code of "reverse" polarity is followed by an impulse of feed-back code of "reverse" polarity.

The impulses of feed-back energy supplied to the relay K move its contact 67 to its normal or reverse position depending upon the polarity of the impulse. On movement of the contact 67 to its normal position, energy flows through the left-hand portion of the primary winding of transformer KT from left to right, and causes an impulse of energy to be induced in the transformer secondary winding. For purposes of illustration, it will be assumed that the transformer windings are arranged so that the impulse of energy induced in the secondary winding at this time flows from left to right in this winding.

If the impulse of feed-back energy of "normal" polarity follows an impulse of master code of "normal" polarity, the movement of the contact of relay K to its normal position occurs at a time when the contacts of relay CTM are picked up.

Accordingly, energy induced in the left-hand portion of the transformer secondary winding flows from the center terminal of the transformer secondary winding through the winding of relay KP from left to right, normal polar contact 70 of relay KP, through winding of relay KN from left to right, asymmetric unit 71, and front contact 65 of relay CTM to the left-hand end terminal of the secondary winding of transformer KT. The impulse of energy supplied to relays KP and KN holds the contacts of relay KP in their normal positions, and energizes the relay KN so that its contacts remain picked up. The transformer KT is so proportioned that the impulse of energy supplied therefrom is of relatively short duration so the impulse is substantially terminated before the contacts of relay CTM release to supply the next impulse of master code to the section rails.

Similarly, when an impulse of feed-back energy of reverse polarity is supplied to relay K and its contact 67 moves to its reverse position, the right-hand portion of the primary winding of transformer KT is energized, and an impulse of energy is induced in the transformer secondary winding which flows from right to left in that winding. If the impulse of feed-back energy of reverse polarity follows an impulse of master

code of reverse polarity, the movement of the contact of relay K to its reverse position will occur at a time when the contacts of relay CTM are released.

Accordingly, energy induced in the right-hand portion of the secondary winding of transformer KT flows from the center terminal of the transformer secondary winding through the winding of relay KP from left to right, normal polar contact 10, winding of relay KN from left to right, asymmetric unit 11, and back contact 65 of relay CTM to the right-hand end terminal of the transformer secondary winding.

The energy supplied to relays KP and KN at this time holds the contacts of relay KP in their normal positions, and maintains the contact of relay KN picked up, while the impulse of energy from the transformer secondary winding terminates before the contacts of relay CTM pick up to supply the next impulse of master code to the section rails.

Accordingly, on continued supply of feed-back energy to relay K, energy is supplied from transformer KT to relays KP and KN, while the contact 65 of relay CTM rectifies the energy supplied from transformer KT to relays KP and KN so that the energy impulses are all of normal polarity.

As explained in the patent of Arthur E. Dodd identified above, the asymmetric units connected across the terminals of relay KN render the relay slow in releasing so its contacts remain picked up during the periods between the impulses of energy supplied to the relay KN.

The contact 12 of relay KN and normal polar contact 14 of relay KP may cooperate to control a circuit which may be employed for any appropriate purpose as, for example, to unlock a switch.

When the section in the rear of the section shown is occupied, relay KHB is released and its contact 66 transfers control of relay PC from reverse polar contact 22 of relay TR to normal polar contact 22 of relay TR. Thereafter, on the supply of an impulse of master code of normal polarity to the track relay TR, relay PC picks up so the impulse of feed-back energy supplied to the section rails is of reverse polarity. Likewise, when an impulse of master code of reverse polarity is supplied to the track relay, the relay PC releases so the impulse of feed-back energy supplied to the section rails is of normal polarity.

When the impulse of feed-back energy of reverse polarity feeds to relay K following an impulse of master code of normal polarity, the contact of relay K will move to its reverse position at a time when the contacts of relay CTM are picked up, and energy from the left-hand portion of the secondary winding of transformer KT will flow from the left-hand end terminal of this winding over front contact 65 of relay CTM, through asymmetric unit 15, normal polar contact 70 of relay KP, and through the winding of relay KP from right to left to the center terminal of the transformer secondary winding. This energy causes the contacts of relay KP to shift to their reverse position so that thereafter energy from the left-hand portion of the transformer secondary winding flows over front contact 65 of relay CTM through asymmetric unit 15, winding of relay KN from left to right, reverse polar contact 70 of relay KP, and through winding of relay KP from right to left to the center terminal of the transformer secondary winding.

Similarly, when the impulse of feed-back energy 75

of normal polarity feeds to relay K following an impulse of master code of reverse polarity, the contact 67 of relay K moves to its normal position at a time when the contacts of relay CTM are released, and energy from the right-hand portion of the secondary winding of transformer KT flows from the right-hand end terminal of the transformer secondary winding over back contact 65 of relay CTM, asymmetric unit 15, through winding of relay KN from left to right, reverse polar contact 70 of relay KP, and through winding of relay KP from right to left to the center terminal of the transformer secondary winding.

Accordingly, when relay KHB is released so that each impulse of master code is followed by an impulse of feed-back energy of opposite polarity, the energy supplied from transformer KT to relays KP and KN is of reverse polarity and the contacts of relay KP occupy their reverse positions, while the contact of relay KN is picked up. When the contacts of relay KP are in their reverse positions, contact 14 interrupts the circuit established in the normal position of the contact, and may establish another circuit which may be employed for any appropriate purpose.

From the foregoing it will be seen that when feed-back energy is supplied to the relay K, an impulse of energy is supplied through the transformer KT to the relays KP and KN on each movement of the contact of relay K, while the energy supplied from the transformer KT is rectified by contact 65 of relay CTM. The operation of contact 65 is such that if the polarity of the feed-back impulses is the same as that of the preceding impulses of master code, the energy supplied from transformer KT to relays KP and KN will be of normal polarity, while if the polarity of the feed-back impulses is opposite from that of the preceding impulses of master code, the energy supplied from the transformer KT to the relays KP and KN will be of reverse polarity. The relays KP and KN distinguish between the two polarities of energy supplied from the transformer and thus provide means for detecting which of the two types of feed-back energy is being supplied over the section rails.

When a train enters the section, the track relay TR ceases to follow code and the supply of feed-back energy is cut off and relay K ceases to follow code so energy is no longer supplied through the transformer KT. Accordingly, relay KN releases and its contacts interrupt the circuits including front contacts of the relay, while the back contacts of the relay may establish circuits which may be employed for any appropriate purpose.

When the section is vacated, master code supplied to the section rails feeds to the track relay TR and operates it so that feed-back energy is again supplied to the section rails so that relay K operates to cause energy to be supplied through transformer KT to relays KP and KN.

Although I have herein shown and described several forms of coded track circuit apparatus embodying my invention, it is understood that various changes and modifications may be made therein within the scope of the appended claims without departing from the spirit and scope of my invention.

Having thus described my invention, what I claim is:

1. In combination, a section of railway track, a first and a second coding relay and a polarized detector relay at the exit end of the section, the first coding relay having contacts continuously actuated between a first and a second position,

the second coding relay having contacts biased to a released position in which they connect the detector relay across the section rails and being movable to a picked-up position in which they cause to be supplied to the section rails energy of normal or reverse polarity according as the contacts of the first coding relay are in their first or their second position, means effective on movement of the contacts of said first coding relay between their two positions in either direction to pick up the contacts of the second coding relay for a predetermined period substantially shorter than the periods that the contacts of the first coding relay remain in each of their two positions, a control relay responsive to movement of a contact of the detector relay between its two positions, a polarized code following track relay at the entrance end of the track section operated by energy supplied over the section rails, and means effective on movement of the track relay contacts to their normal position to supply to the section rails an impulse of energy of one polarity and effective on movement of the track relay contacts to their reverse position to supply to the section rails an impulse of energy of the other polarity.

2. In combination, a section of railway track, a first and a second coding relay and a polarized detector relay at the exit end of the section, the first coding relay having contacts continuously actuated between a first and a second position, the second coding relay having contacts biased to a released position in which they connect the detector relay across the section rails and being movable to a picked-up position in which they cause to be supplied to the section rails energy of normal or reverse polarity according as the contacts of the first coding relay are in their first or their second position, means effective on movement of the contacts of said first coding relay between their two positions in either direction to pick up the contacts of the second coding relay for a predetermined period substantially shorter than the periods that the contacts of the first coding relay remain in each of their two positions, a control relay responsive to movement of a contact of the detector relay between its two positions, a polarized code following track relay at the entrance end of the track section operated by energy supplied over the section rails, an auxiliary relay responsive to movement of a contact of said track relay between its two positions, means effective when said auxiliary relay is picked up to supply to the section rails an impulse of energy of one polarity on movement of the track relay contacts to their normal position and to supply to the section rails an impulse of energy of the other polarity on movement of the track relay contacts to their reverse position, and means effective when said auxiliary relay is released to alternately connect said track relay and a supply circuit across the section rails and to cause alternate impulses of energy supplied over said supply circuit to the section rails to be of opposite polarities.

3. In combination, a section of railway track, a polarized code following detector relay at the exit end of said section, a control relay responsive to movement of a contact of the detector relay between its two positions, code transmitting means for alternately connecting said detector relay and a supply circuit across the section rails and for causing the impulses of energy supplied over said supply circuit to the section rails to be of alternately opposite polarities, a polarized code fol-

lowing track relay at the entrance end of said section operated by energy supplied over the section rails, an auxiliary relay responsive to movement of a contact of said track relay between its two positions, means effective when said auxiliary relay is picked up to supply to the section rails an impulse of energy of one polarity on movement of the track relay contacts to their normal position and to supply to the section rails an impulse of energy of the other polarity on movement of the track relay contacts to their reverse position, and means effective when said auxiliary relay is released to alternately connect said track relay and a supply circuit across the section rails and to cause alternate impulses of energy supplied over said supply circuit to be of opposite polarities.

4. In combination, a section of railway track, a polarized code following detector relay at the exit end of said section, a control relay responsive to movement of a contact of said detector relay between its two positions, a first coding relay having contacts continuously actuated between a first and a second position, a second coding relay having contacts biased to a released position in which they connect the track rails across the detector relay winding and being movable to a picked-up position in which they connect the track rails across a pair of supply conductors over which is supplied direct current of one polarity or the other according as the contacts of the first coding relay are in their first or their second position and over which alternating current is supplied when the control relay is released, means effective on movement of the contacts of the first coding relay between their two positions in either direction when the control relay is picked up to pick up the contacts of said second coding relay for a predetermined period substantially shorter than the periods that the contacts of the first coding relay remain in each of their two positions, means effective when the control relay is released to pick up the contacts of the second control relay as long as the contacts of the first control relay are in a selected one of their two positions, a polarized code following track relay at the entrance end of the section operated by energy supplied over the section rails, an auxiliary relay responsive to movement of a contact of said track relay between its two positions, means effective when said auxiliary relay is picked up to supply to the section rails an impulse of energy of one polarity on movement of the track relay contacts to their normal position and to supply to the section rails an impulse of energy of the other polarity on movement of the track relay contacts to their reverse position, and means effective when said auxiliary relay is released to alternately connect said track relay and a supply circuit across the section rails and to cause alternate impulses of energy supplied over said supply circuit to the section rails to be of opposite polarities.

5. In combination, a section of railway track, a polarized code following detector relay at the exit end of said section, a control relay responsive to movement of a contact of the detector relay between its two positions, code transmitting means for alternately connecting said detector relay and a supply circuit across the section rails and for causing the impulses of energy supplied over said supply circuit to the section rails to be of alternately opposite polarities, a polarized code following track relay at the entrance end of said section operated by energy supplied over the sec-

tion rails, an auxiliary relay responsive to movement of a contact of said track relay between its two positions, an impulse relay having contacts biased to a released position in which they connect the section rails across the terminals of the winding of said track relay and movable therefrom to a picked-up position in which they connect the section rails across a pair of supply conductors over which energy is supplied to the section rails, a pole changing relay having contacts biased to a released position in which they cause the energy supplied over said supply conductors to be of one polarity and movable therefrom to a pick-up position in which they cause the energy supplied over said supply conductors to be of the other polarity, means effective on movement of the track relay contacts between their two positions in either direction when the auxiliary relay is picked up to momentarily pick up the contacts of said impulse relay, means effective on movement of the track relay contacts to a selected one of their positions when the auxiliary relay is picked up to pick up the contacts of said pole changing relay, and means effective when the auxiliary relay is released to continuously actuate the contacts of said impulse relay between their released and picked-up positions and to control the pole changing relay in such manner that the impulses of energy supplied to the section rails as a result of picking up of said impulse relay are of alternately opposite polarities.

6. In combination, a section of railway track, a polarized code following detector relay at the exit end of said section, a control relay responsive to movement of a contact of the detector relay between its two positions, code transmitting means for alternately connecting said detector relay and a supply circuit across the section rails and for causing the impulses of energy supplied over said supply circuit to the section rails to be of alternately opposite polarities, a polarized code following track relay at the entrance end of said section operated by energy supplied over the section rails, an auxiliary relay responsive to movement of a contact of said track relay between its two positions, an impulse relay having contacts biased to a released position in which they connect the section rails across the terminals of the winding of said track relay and movable therefrom to a pick-up position in which they connect the section rails across a pair of supply conductors over which energy is supplied to the section rails, a pole changing relay having contacts biased to a released position in which they cause the energy supplied over said supply conductors to be of one polarity and movable therefrom to a picked-up position in which they cause the energy supplied over said supply conductors to be of the other polarity, a circuit including a front contact of said auxiliary relay for supplying to the impulse relay an impulse of energy on movement of the track relay contacts between their two positions in either direction, a circuit including a front contact of said auxiliary relay for supplying energy to said pole changing relay when the track relay contacts are in a selected one of their two positions, a circuit including a back contact of said auxiliary relay and a front contact of said pole changing relay for supplying energy to said impulse relay, and a circuit including back contacts of said impulse and auxiliary relays for supplying energy to said pole changing relay.

7. In combination, a section of railway track, 75

a polarized code following detector relay at the exit end of said section, a control relay responsive to movement of a contact of the detector relay between its two positions, code transmitting means for alternately connecting said detector relay and a supply circuit across the section rails and for causing the impulses of energy supplied over said supply circuit to the section rails to be of alternately opposite polarities, a polarized code following track relay at the entrance end of said section operated by energy supplied over the section rails, an impulse relay having a contact biased to a released position in which it connects the section rails across the terminals of the winding of said track relay and movable to a picked-up position in which it connects the section rails across a pair of supply conductors in series with the winding of said track relay, a contact of said track relay controlling the polarity of the energy supplied over said supply conductors in such manner that energy of one polarity is supplied in one position of the track relay contact and energy of the other polarity is supplied in the other position of the track relay contact and so that in each position of the track relay contact the energy supplied through the track relay winding holds the track relay contacts in the position which they then occupy, and means for supplying an impulse of energy to said impulse relay on movement of the track relay contacts between their two positions in either direction.

8. In combination, a section of railway track, a polarized code following detector relay at the exit end of said section, a coding relay having a contact movable between a first position in which it connects the section rails across the terminals of the winding of said detector relay and a second position in which it connects the section rails across a pair of supply conductors in series with the winding of said detector relay, a contact of said detector relay controlling the polarity of the energy supplied over said supply conductors in such manner that energy of one polarity is supplied in one position of the detector relay contact and energy of the other polarity is supplied in the other position of the detector relay contact and so that in each position of the detector relay contact the energy supplied through the detector relay winding holds the relay contacts in the position which they then occupy, a polarized code following track relay at the entrance end of said section operated by energy supplied over the section rails, an auxiliary relay responsive to movement of a contact of said track relay between its two positions, means effective when said auxiliary relay is picked up to supply to the section rails an impulse of energy of one polarity on movement of the track relay contacts to their normal position and to supply to the section rails an impulse of energy of the other polarity on movement of the track relay contacts to their reverse position, and means effective when said auxiliary relay is released to alternately connect said track relay and a supply circuit across the section rails and to cause alternate impulses of energy supplied to the section rails to be of opposite polarities.

9. In combination, a section of railway track, a first and a second coding relay and a polarized detector relay at the exit end of the section, the first coding relay having contacts continuously actuated between a first and a second position, the second coding relay having contacts biased to a released position in which they connect the detector relay across the section rails and being

movable to a picked-up position in which they cause to be supplied to the section rails energy of normal or reverse polarity according as the contacts of the first coding relay are in their first or their second position, means effective on movement of the contacts of said first coding relay between their two positions in either direction to pick up the contacts of the second coding relay for a predetermined period substantially shorter than the periods that the contacts of the first coding relay remain in each of their two positions, a polarized code following track relay at the entrance end of the section operated by energy supplied over the section rails, means effective on movement of the track relay contacts between their two positions in either direction to supply an impulse of energy to the section rails, means for controlling the polarity of the energy impulses supplied to the section rails as a result of operation of the track relay in such manner that at times energy of normal polarity is supplied to the section rails on movement of the track relay contacts to their normal position and energy of reverse polarity is supplied to the section rails on movement of the track relay contacts to their reverse position and at other times energy of reverse polarity is supplied to the section rails on movement of the track relay contacts to their normal position and energy of normal polarity is supplied to the section rails on movement of the track relay contacts to their reverse position, polarized control means at the exit end of said section, means responsive to movement of a contact of said detector relay between its two positions for supplying energy to said control means, and means governed by the relative positions of the contacts of said detector relay and of said first coding relay for determining the polarity of the energy supplied to said control means.

10. In combination, a section of railway track, a first and a second coding relay and a polarized detector relay at the exit end of the section, the first coding relay having contacts continuously actuated between a first and a second position, the second coding relay having contacts biased to a released position in which they connect the detector relay across the section rails and being movable to a picked-up position in which they cause to be supplied to the section rails energy of normal or reverse polarity according as the contacts of the first coding relay are in their first or their second position, means effective on movement of the contacts of said first coding relay between their two positions in either direction to pick up the contacts of the second coding relay for a predetermined period substantially shorter than the periods that the contacts of the first coding relay remain in each of their two positions, a polarized code following track relay at the entrance end of the section operated by energy supplied over the section rails, means effective on movement of the track relay contacts between their two positions in either direction to supply an impulse of energy to the section rails, means for controlling the polarity of the energy impulses supplied to the section rails as a result of operation of the track relay in such manner that at times energy of normal polarity is supplied to the section rails on movement of the track relay contacts to their normal position and energy of reverse polarity is supplied to the section rails on movement of the track relay contacts to their reverse position and at other times energy of reverse polarity is supplied to the section rails on movement of the track relay contacts to their normal position and energy of normal polarity is supplied to the section rails on movement of the track relay contacts to their reverse position.

75

movement of the track relay contacts to their normal position and energy of normal polarity is supplied to the section rails on movement of the track relay contacts to their reverse position, 5 polarized control means at the exit end of said section, and means for supplying energy of one polarity to said control means if the detector relay contact moves to its normal position when the contacts of the first coding relay are in their first 10 position and if the detector relay contact moves to its reverse position when the contacts of the first coding relay are in their second position and for supplying energy of the other polarity to said control means if the detector relay contact moves to its normal position when the contacts of the first coding relay are in their second position and if the detector relay contact moves to its reverse position when the contacts of the first coding relay are in their first position.

11. In combination, a section of railway track, a polarized code following detector relay at the exit end of said section, a coding relay having contacts continuously actuated between a first and a second position, means effective on movement of the contacts of said coding relay to their first position to supply to the section rails an impulse of energy of normal polarity and to thereafter connect the detector relay across the section rails, means effective on movement of the contacts of said coding relay to their second position to supply to the section rails an impulse of energy of reverse polarity and to thereafter connect the detector relay across the section rails, polarized control means at the exit end of the section, means for supplying energy of one polarity to said control means if the detector relay contact moves to its normal position when the contacts of said coding relay are in their first position and if the detector relay contact moves to its reverse position when the contacts of said coding relay are in their second position, means for supplying energy of the other polarity to said control means if the detector relay contact moves to its normal position when the contacts of said coding relay are in their second position and if the detector relay contact moves to its reverse position when the contacts of said coding relay are in their first position, a polarized code following track relay at the entrance end of the section operated by energy supplied over the section rails, means effective on movement of the track relay contacts between their two positions in either direction to supply an impulse of energy to the section rails, means for controlling the polarity of the energy impulses supplied to the section rails as a result of operation of the track relay in such manner that at times energy of normal polarity is supplied to the section rails on movement of the track relay contacts to their normal position and energy of reverse polarity is supplied to the section rails on movement of the track relay contacts to their reverse position and at other times energy of reverse polarity is supplied to the section rails on movement of the track relay contacts to their normal position and energy of normal polarity is supplied to the section rails on movement of the track relay contacts to their reverse position.

12. In combination, a section of railway track, a polarized code following detector relay at the exit end of said section, a coding relay having contacts continuously actuated between a first and a second position, means effective on movement of the contacts of said coding relay to their first position to supply to the section rails

an impulse of energy of normal polarity and to thereafter connect the detector relay across the section rails, means effective on movement of the contacts of said coding relay to their second position to supply to the section rails an impulse of energy of reverse polarity and to thereafter connect the detector relay across the section rails, polarized control means at the exit end of the section, a transformer, a circuit including a contact of said detector relay for supplying energy from a source of direct current to the primary winding of said transformer, a circuit including a contact of said coding relay for supplying energy from the secondary winding of said transformer to said control means, the circuits of the transformer primary and secondary windings being arranged so that if the detector relay contact moves to its normal position when the coding relay contact is in its first position or if the detector relay contact moves to its reverse position when the coding relay contact is in its second position impulses of energy of one polarity are supplied to the control means and so that if the detector relay contact moves to its normal position when the coding relay contact is in its second position or if the detector relay contact moves to its reverse position when the coding relay contact is in its first position impulses of energy of the other polarity are supplied to the control means, a polarized code following track relay at the entrance end of the section operated by energy supplied over the section rails, means effective on movement of the track relay contacts between their two positions in either direction to supply an impulse of energy to the section rails, means for controlling the polarity of the energy impulses supplied to the section rails as a result of operation of the track relay in such manner that at times energy of normal polarity is supplied to the section rails on movement of the track relay contacts to their normal position and energy of reverse polarity is supplied to the section rails on movement of the track relay contacts to their reverse position and at other times energy of reverse polarity is supplied to the section rails on movement of the track relay contacts to their normal position and energy of normal polarity is supplied to the section rails on movement of the track relay contacts to their reverse position.

13. In combination, a section of railway track through which are operated in a given direction locomotives equipped with cab signal apparatus responsive to flow of coded alternating current in the track rails, a coding relay at the exit end of the section having a contact biased to a released position in which it connects a code following feed-back detector relay across the section rails and movable therefrom to a picked-up position in which it connects a track battery and the secondary winding of a track transformer across the section rails, a control relay having contacts which are picked up when and only when said detector relay is operated by feed-back energy supplied over the section rails, a coding device having contacts continuously actuated between a first and a second position, means effective on movement of the coding device contact to its first position when said control relay is picked up to pick up the coding relay contact for a period substantially shorter than the period during which the coding device contact remains in said first position, means effective on movement of the coding device contact to its first position when said control relay is released to pick up the

coding relay contact for a period substantially as long as the period during which the coding device contact remains in said first position, means for supplying energy to the track transformer primary winding only when said control relay is released, a code following track relay at the entrance end of said track section operated by energy supplied over the section rails from said track battery, and means associated with said track relay for supplying impulses of feed-back energy to the section rails in the intervals between impulses of energy supplied from said track battery.

14. In combination, a section of railway track through which are operated in a given direction locomotives equipped with cab signal apparatus responsive to flow of coded alternating current in the track rails, a coding relay at the exit end of the section having a contact biased to a released position in which it connects a code following feed-back detector relay across the section rails and movable therefrom to a picked-up position in which it connects a track battery and the secondary winding of a track transformer across the section rails, a control relay having contacts which are picked up when and only when said detector relay is operated by feed-back energy supplied over the section rails, a coding device having contacts continuously actuated between a first and a second position, means effective on movement of the coding device contact to a selected one of its positions when said control relay is picked up to pick up the coding relay contact for a period substantially shorter than the period during which the coding device contact remains in said selected one of its positions, means effective on movement of the coding device contact to a selected one of its positions when said control relay is released to pick up the coding relay contact for a period substantially as long as the period during which the coding device contact remains in said selected one of its positions, means for supplying energy to the track transformer primary winding only when said control relay is released, a code following track relay at the entrance end of said track section operated by energy supplied over the section rails from said track battery, and means associated with said track relay for supplying impulses of feed-back energy to the section rails in the intervals between impulses of energy supplied from said track battery.

15. In combination, a section of railway track through which are operated in a given direction locomotives equipped with cab signal apparatus responsive to flow of coded alternating current in the track rails, a coding relay at the exit end of the section having a contact biased to a released position in which it connects a code following feed-back detector relay across the section rails and movable therefrom to a picked-up position in which it connects a track battery and the secondary winding of a track transformer across the section rails, a control relay having contacts which are picked up when and only when said detector relay is operated by feed-back energy supplied over the section rails, a coding device having contacts continuously actuated between a first and a second position, means effective on movement of the coding device contact to a selected one of its positions when said control relay is picked up to pick up the coding relay contact for a period substantially shorter than the period during which the coding device contact remains in said selected one of its positions, means effective on movement of the coding device contact to a selected one of its positions when said control relay is released to pick up the coding relay contact for a period substantially as long as the period during which the coding device contact remains in said selected one of its positions, means for supplying energy to the track transformer primary winding only when said control relay is released, a code following track relay at the entrance end of said track section operated by energy supplied over the section rails from said track battery, and means associated with said track relay for supplying impulses of feed-back energy to the section rails in the intervals between impulses of energy supplied from said track battery.

16. In combination, a section of railway track through which are operated in a given direction locomotives equipped with cab signal apparatus responsive to flow of coded alternating current in the track rails, a coding relay at the exit end of the section having a contact biased to a released position in which it connects a code following feed-back detector relay across the section rails and movable therefrom to a picked-up position in which it connects a track battery and the secondary winding of a track transformer across the section rails, a control relay having contacts which are picked up when and only when said detector relay is operated by feed-back energy supplied over the section rails, a coding device having contacts continuously actuated between a first and a second position, means effective on movement of the coding device contact to a selected one of its positions when said control relay is picked up to pick up the coding relay contact for a period substantially shorter than the period during which the coding device contact remains in said selected one of its positions, means effective on movement of the coding device contact to a selected one of its positions when said control relay is released to pick up the coding relay contact for a period substantially as long as the period during which the coding device contact remains in said selected one of its positions, means for supplying energy to the track transformer primary winding only when said control relay is released, a code following track relay at the entrance end of said track section operated by energy supplied over the section rails from said track battery, and means associated with said track relay for supplying impulses of feed-back energy to the section rails in the intervals between impulses of energy supplied from said track battery.

tive on movement of the coding device contact to a selected one of its positions when said control relay is released to pick up the coding relay contact for a period substantially as long as the period during which the coding device contact remains in said selected one of its positions; means for supplying energy to the track transformer primary winding only when said control relay is released, a code following track relay at the entrance end of said track section operated by energy supplied over the section rails from said track battery, an auxiliary relay which is picked up when and only when said track relay is responding to coded energy, means effective when said auxiliary relay is picked up to supply to the section rails at the entrance end thereof impulses of feed-back energy during the intervals between impulses of energy supplied from said track battery, and means effective when said auxiliary relay is released to alternately connect the track relay and a source of feed-back energy across the section rails.

16. In combination, a section of railway track through which are operated in a given direction locomotives equipped with cab signal apparatus responsive to flow of coded alternating current in the track rails, a coding relay at the exit end of the section having a contact biased to a released position in which it connects a code following feed-back detector relay across the section rails and movable therefrom to a picked-up position in which it connects a track battery and the secondary winding of a track transformer across the section rails, a control relay having contacts which are picked up when and only when said detector relay is operated by feed-back energy supplied over the section rails, a coding device having contacts continuously actuated between a first and a second position, an impulse transformer proportioned so that on a change in energization of its primary winding there is supplied from its secondary winding an impulse of energy effective to pick up the coding relay contact and maintain it picked up for a period substantially shorter than the periods during which the coding device contact remains in each of its two positions, a circuit governed by a contact of said coding device for supplying energy to the primary winding of said impulse transformer, a circuit including a front contact of said control relay for supplying energy from the impulse transformer secondary winding to said coding relay, a circuit including a back contact of said control relay and a contact of said coding device for supplying energy to said coding relay, means for supplying energy to the track transformer primary winding only when said control relay is released, a code following track relay at the entrance end of said track section operated by energy supplied over the section rails from said track battery, and means associated with said track relay for supplying impulses of feed-back energy to the section rails in the intervals between impulses of energy supplied from said track battery.

17. In combination, a section of railway track through which are operated in a given direction locomotives equipped with cab signal apparatus responsive to flow of coded alternating current in the track rails, a coding relay at the exit end of the section having a contact biased to a released position in which it connects a code following feed-back detector relay across the section rails and movable therefrom to a picked-up position in which it connects a track battery and the sec-

ondary winding of a track transformer across the section rails, a control relay having contacts which are picked up when and only when said detector relay is operated by feed-back energy supplied over the section rails, a coding device having contacts continuously actuated between a first and a second position, a repeater relay having a contact movable between a first and a second position, a circuit including a front contact of said control relay and a contact of said coding device for energizing said repeater relay to cause the contacts of said repeater relay to move to their first or their second position according as the coding device contacts occupy their first or their second position, a circuit for supplying energy to said coding relay when the contacts of said coding device and of said repeater relay are out of correspondence, means for supplying energy to the track transformer primary winding only when said control relay is released, a code following track relay at the entrance end of said track section operated by energy supplied over the section rails from said track battery, and means associated with said track relay for supplying impulses of feed-back energy to the section rails in the intervals between impulses of energy supplied from said track battery.

18. In combination, a section of railway track, a polarized code following detector relay at the exit end of said section, a control relay responsive to movement of a contact of said detector relay between its two positions, a coding relay having contacts continuously actuated between a first and a second position, means effective on each movement of the contacts of said coding relay between their two positions in either direction when said control relay is picked up to connect the track rails across a pair of supply conductors for an interval substantially shorter than the periods that the contacts of said coding relay remain in each of their two positions and to thereafter connect said detector relay across the track rails during the remainder of such period, means effective when said control relay is released to connect the track rails across said supply conductors as long as the coding relay contacts are in their first position and to connect said detector relay across the track rails as long as the coding relay contacts are in their second position, means effective when said control relay is picked up to cause to be supplied to the track rails over said supply conductors direct current of one polarity or the other according as the contacts of said coding relay are in their first or their second position, means effective when said control relay is released to cause alternating current to be supplied to the track rails over said supply conductors, a polarized code following track relay at the entrance end of the section operated by energy supplied over the section rails, an auxiliary relay responsive to movement of a contact of said track relay between its two positions, means effective when said auxiliary relay is picked up to supply to the section rails an impulse of energy of one polarity on movement of the track relay contacts to their normal position and to supply to the section rails an impulse of energy of the other polarity on movement of the track relay contacts to their reverse position, and means effective when said auxiliary relay is released to alternately connect said track relay and a supply circuit across the section rails and to cause alternate impulses of energy supplied over said supply circuit to the section rails to be of opposite polarities.

ARTHUR L. JEROME.
